BY *J. W. Robertson*,

ATTORNEY.

UNITED STATES PATENT OFFICE.

WILLIAM S. SHARPNECK, OF DENVER, COLORADO.

JOURNAL-BOX.

SPECIFICATION forming part of Letters Patent No. 392,465, dated November 6, 1888.

Application filed November 7, 1887. Renewed August 25, 1888. Serial No. 283,702. (No model.)

To all whom it may concern:

Be it known that I, WILLIAM S. SHARPNECK, a citizen of the United States, residing at Denver, in the county of Arapahoe and State of Colorado, have invented certain new and useful Improvements in Anti-Friction Journal-Boxes, of which the following is a specification, reference being had therein to the accompanying drawings, in which—
10 Figure 1 is a central vertical section of a journal-box constructed according to my improvement; Fig. 2, a transverse section through the line *x x* in Fig. 1, and Fig. 3 is a perspective view of a part detached, on a larger scale.
15 This invention relates to an improvement on the journal-box shown in my allowed application, No. 228,374, filed February 21, 1887; and it consists in the peculiar construction, arrangement, and combinations of parts, herein
20 after more particularly described, and then definitely pointed out in the claims.

Referring now to the details of construction, A represents the case, provided with a hinged cap, *a*, carrying a disk, B, and bails *b* to receive the end-thrust of the axle C, as shown in my said application, No. 228,374. Surrounding the axle is a series of hollow rollers, D, having in each a series of smaller rollers, E, arranged around a central pin, F, the ends of which enter 25 separating-washers G, forming a kind of cage, as fully shown and described in my aforesaid application. Resting on these rollers is a box, H, (see Fig. 3,) having at each end a circular groove, *h*, and a preferably angular or flattened 30 V-shaped groove, *h'*, on its top. In each of these circular grooves is one or more balls, I, which bear against the vertical edge of the groove and the outer faces of the separating-washers G.
35 In the angular top groove, *h'*, is a roller, J, extending transversely of the box and working in said groove *h'*, and a groove, *a'*, of corresponding shape in the under side of the top of the casing A. By this arrangement the weight

that rests on the transverse roller J will keep 45 the box in its proper relative position on the shaft, and at the same time allow the same and the rolls to travel freely with the shaft, while the balls I will hold the cage and rolls in their proper position also without the necessity of 50 any groove in the rolls or bead on the shaft, as in my aforesaid application, which practice has been shown to be somewhat objectionable.

Other equivalent devices may be used in lieu of the balls I and roller J, such as balls in place of 55 the roll J, and tapering rolls in lieu of the balls I; but I prefer the devices shown. I should, however, consider the use of tapering rolls in place of said balls I, and balls in lieu of the roller J, as equivalent devices for those I employ, and 60 intend to be understood as claiming the same in the following claims.

What I claim as new is—

1. The combination, with an axle, of a box and casing for the same, provided with corresponding inclined-sided grooves at right angles to said axle, and a roller set in said grooves, and the grooves shaped to normally retain the roller in one position therein, substantially as described. 65

2. The combination, with a shaft, of a box for the same, a set of rolls surrounding the shaft, and balls at each end of said rolls, to retain them in their proper relative positions, as set forth. 70

3. The combination, with a shaft, of a set of 75 anti-friction rolls surrounding the same, a box resting on said rolls, having downwardly-projecting ends, provided with circular grooves in said ends, and balls in said grooves, all constructed and arranged substantially as described. 80

In testimony whereof I affix my signature, in presence of two witnesses, this 5th day of November, 1887.

WILLIAM S. SHARPNECK.
